CLAIM

The ornamental design for a carrying bag light assembly, as shown and described.

DESCRIPTION

FIG. 1 is a front elevation view of a carrying bag light assembly showing my new design;

FIG. 2 is a rear elevation view;

FIG. 3 is a left elevation view;

FIG. 4 is a right elevation view;

FIG. 5 is a top plan view;

FIG. 6 is a bottom plan view; and,

FIG. 7 is a front isometric view.
